DIAVISION

Aloysius J. Cawley, Pittston, Pa.

Application January 30, 1930, Serial No. 424,743

16 Claims. (Cl. 250—1)

The invention relates to the perception of objects by means of electric waves which are of a length greater than light waves, particularly those of small wave length, permitting navigation to go on in harbors and the like at a normal rate in heavy mists. Briefly it relates to the perception of electrically conducting media through ionconducting media by means of radio waves, consequently one of its modifications comprises the detection of metallic objects in a brick, concrete or wooden building. Many other similar uses will immediately suggest themselves.

An invisible image is formed by means of a lens, and this is rendered visible by means of stationary or moving resonators placed in the image field. Those resonators are provided with means for converting electrical energy into visible light. An auxiliary vacuum tube reception detector-amplifier apparatus may be used to operate in synchronism with the apparatus in order to obtain a more brilliant image.

A series of resonators is provided in one modification, which may be used without the electric wave forming means, whereby it is possible to detect both the direction and identity of the source of the waves being received.

Radio waves of a known frequency and plane of polarization are directed by means of suitable reflectors upon the objects to be perceived. Coils, or separate electrodes of suitable frequency or tuning characteristics to respond in the greatest degree to those waves are placed in a position to further respond with the greatest facility to the waves, due to the position of their vibration or polarization. The coils or resonators in one modification are made movable in the visual field to attain economy in construction, as one moving coil takes the place of many stationary coils.

Reference is to be had to the accompanying drawings forming part of this specification, in which like reference characters have similar meanings in all of the views, and in which,

Figure 1 is an elevational view of the space in which the visual image is to be formed, showing the arrangement of the electrodes which are here illustrated as being unconnected, which detect the incoming waves and render the gas luminous. Figures 1a, 1b, 1c and 1d illustrate different modifications of the manner of connecting the resonators.

Figure 2 is a side elevational view of another modification, partly in cross section of the gas space which is rendered luminous by the waves, showing the resonators which coat with the

incoming waves. The auxiliary means for detecting the incoming waves and assisting the gas space and resonators in rendering them visible is also shown. Figures 2a and 2b are elevational views, partly in cross-section, illustrating modifications having special arrangements of the electrodes and resonators.

Figure 3 is a side elevational view of an apparatus partly in cross-section, which may be used without an electric wave lens for showing the direction and identity of the source of incoming waves.

Figure 4 is an exaggerated elevational side view of a resonator coil and its surrounding ionized gas space, a large number of such coils being used to render a luminous image of objects.

Figure 5 is an illustration of a modification of the complete system in use, showing the transmission of the electromagnetic wave beams, their concentration and dirigibility, their focusing into an invisible image, and the rendering of this image visible by means of rotating coils and neon tubes.

Figure 6 shows an illustration of one of the carriers for moving the coils and tubes through the image field in a definite direction and position, the latter being that giving the greatest response to the waves; it, together with Figures 6a, 6b, 6c and 6d, shows the arrangement of the coils and carriers; Figure 6c shows one of the many ways in which the coils may be attached. In those modifications, a disk is used as the supporting and moving medium.

Figures 7, 7a, 7b, 7c and 7d show some of the many modifications of the coils and luminous tubes that may be utilized without departing from the spirit of the invention.

Figure 8 is an illustration of the coils and luminous tubes attached to a carrier arm.

Figure 9 is an illustration of a special type of rotatable element for converting the invisible image into a visible one.

Figure 9a illustrates a modification of Figure 9.

The arrangement and operation of the camera-like structure for rendering an electric wave image luminous was described in my copending application of October 20, 1921, Serial Number 509,163, and is also described in my copending application, Serial No. 523,791, of March 19, 1931, which is also a continuation-in-part application of the 1921 application. It depended upon the fact that scientists have formed an image by means of large lenses of bitumen or other electric wave permeable substance, in the same manner as Hertz has demonstrated their refrangi-

bility by means of prisms of this material. The type of resonator there described is shown in Figure 2. It is a preferably insulated conductor connecting electrodes in an ionized gas chamber. Figures 1, 1a, 1b, 1c and 1d illustrate various means of connecting electrodes 6 by means of those resonators, or conductors 8. Figure 1 illustrates a modification in which the electrodes are unconnected. The incoming electric waves 10 generate electromotive force, and a consequent current in them. The current passes through an ionized gas space 12 with great ease, due to the low pressure existing in this space. At 5 in Figure 1b a diagonal arrangement of resonators, such 15 as 8, 8a, 8b and 8c of Figures 2, 2a and 2b is shown. At 9 of Figure 1c another vertical and horizontal arrangement is shown. At 10 of Figure 1d still another more complicated arrangement is illustrated. Figure 2 shows that the 20 source of power is connected by means of coils 1 to electrodes 7, and these latter connected directly with the contained ionized gas. This arrangement may be compared to a quenched spark gap, as many small metallic particles are provided 25 to conduct the charge or current, but of course with the distinction that the air or neon, helium, etc., is of low pressure and readily permits the flow of proper electric currents. 14 of Figure 2 is a detector amplifier and modulator, if desired, 30 arrangement for producing synchronous electrical currents in space 12, and as a result of capacity in resonators 8, 8a, whether simply straight conductors preferably insulated, or coils of fine wire. If 14 is placed in proper adjustment 35 with reference to the incoming waves, it will act to keep the gas space 12 and associated resonators in such electrical condition that a very slight current is necessary in resonators, such as 8a, 8b, etc., to generate sufficient intensity 40 to represent the "high lights" of the image of electric waves. By adjusting either coil or detector amplifier, a condition is maintained wherein there is always an almost imperceptible, or a sub-visual luminosity. The operation of the 45 resonators by means of the current passing in gas space 12 will be understood by considering that they act in a manner dependent upon their capacity, and by the fact that a passing current always influences neighboring circuits. By placing 50 conductors 8 in front of electric wave permeable plate 2, they will be in unhindered contact with the wave at its fullest intensity, as when placed in the gas space, due to the fact that there is no such thing as a perfectly transparent 55 substance for electric waves, be they light waves or other waves. They are really subjected to waves that have suffered more or less by absorption in 2 when placed in the gas space.

In order to further understand the operation 60 of the apparatus illustrated in Figures 1, 1a, 1b, 1c, 1d, 2, 2a and 2b when used in connection with the camera-like structure of the above mentioned application, reference must be had to Figure 4. Coil 8a may be made of many turns 65 of fine wire, if desired, and since it is placed in the camera in a position in which its plane is at right angles to the focal plane of the electrical image, constitutes a virtual wave detector, as in this position it receives electric waves in such 70 manner as to permit them to generate the greatest possible currents in vertical members 3 and 4. Moreover, they have a specificity for waves of a certain length, but are not limited in their reception thereto. If the incoming wave is of 75 such a length that its crest is at 4 when its trough

is at 3, then the greatest possible current is generated. Waves of less than a centimeter in length have been generated by use of apparatus utilizing spark gaps. If the distance between 3 and 4 is a half-centimeter, the sharpest reception would be for waves of one centimeter. Waves of much greater length will affect the apparatus. But suitable reflectors are used with the apparatus for concentrating the waves being sent out in a beam, as by reflectors made of wires, and having the waves of short wave length, very much shorter than any ever even attempted commercially, a new type of wireless communication could be built up. If objects could be perceived at a distance of five miles, tremendous advantages would result in the speeding up of navigation in harbors, and in the railroad traffic of the country. Very short waves like those are not used for the commercial transmission of messages. Exceedingly short waves are desirable in the formation of an image, due to the refraction required. Much longer waves may be detected by use of device like that of Figure 3. The apparatus consists of a number of coils 8, 8', and 8'' with the usual gas space 12. However 17 is a reflector of electric waves, and by reflecting them back in the direction in which they came, there will be a superposition of crest upon crest at the vertical portion corresponding to 4 of Figure 4, and greater concentration showing direction of the signals, in addition to their sense. If the distance between portions as of 3 and 4 is one half meter, the wave length which gives the greatest luminosity is one meter. This would give the identity of the sender, if each light house or the like had a definite known wave length.

If the coils, such as 8a, Figure 4, have many turns, then the greater the number of vertical members in 3 and 4, the longer will be the wavelength that it will respond to. Several conductors in 3 and 4 correspond to a conductor in general, equal in length to the sum of the lengths. Thus, though 4 may be extremely short, it would equal an antennae of many times its length in wave reception. All of those coils, whether consisting of several turns or whether consisting of an upright single insulated member, correspond to a resonator such as those used by Hertz, but with the distinction that this consists of a column of gas instead of a metal wire with two spark balls enclosing the gap. The column of gas is a conductor of electricity, and may have electric currents generated in it like an conductor by means of electric waves. By having many turns of fine wire in the coil, a current of high electromotive force is generated, in it by the incoming electric waves, and this aids in forcing it through the gas. The coils, therefore, may be very minute and thus give great detail to the image. The coil, moreover, has distributed capacity as well as inductance, which is increased by keeping the turns close together.

Gas space 12 may be made more sensitive to electrical discharges if desired by causing the rays from the ultraviolet lamp to fall upon it and thus render the apparatus far more sensitive. The electrodes 6 may be made of a metal if desired, such as that used in certain lamps, or sources of ultraviolet light.

The insulated vertical member 8 has utility in the reception of short waves, as a coil of small inductance and small distributed capacity is best.

The apparatus may be regarded as a development of the apparatus of Hertz. Hundreds of

resonators are used just as he used them, but are arranged in a focal plane. Instead of his feeble means of generating oscillations, large, powerful means are used having the same strength as those used commercially to generate the much longer waves which are now used for wireless communication. Those short, quasi-optical waves will be concentrated in the form of a beam by means of suitable metallic wire, or other reflectors in order that all of the energy may be concentrated in a definite direction. Waves a few millimeters long have been generated by use of spark gaps. Short waves readily permit their use in forming images by means of suitable lenses.

A shore station might send a beam at least as far as light is ordinarily discernible by ships in clear weather. That is, it would have the same range as a lighthouse has in clear weather, but of course its signals would be discernible in all kinds of weather.

Each coil may be also looked upon as a minute direction finder, and therefore is placed at its most sensitive position with regard to the incoming electric waves forming the image.

The camera body should be electric wave proof, and this may be accomplished in various ways, one of which is by covering it with metal foil of suitable thickness in order to protect the gas space from stray waves.

Figure 5 is an illustration of the application of the apparatus to discerning the presence and position of steamships during fogs and mists. Any generator of high frequency electricity of suitable type is indicated by 26. A row of short wave generators, such as short conductors, or a plurality of Rhighi gaps is indicated at 24; this may consist of many rows of many generators. These are connected to the source of high frequency electricity 26. The waves thus generated are reflected by the cylindrical reflector 23. They are somewhat similar to generators described in my application Serial Number 376,743, Power transmission system, filed July 8, 1929. The waves are polarized in a definite plane, and if the receiving resonators to be described later are placed in a position to respond most readily to those waves, great sensitiveness is given the apparatus. It is to be noted that reflector 23 is cylindrical and parabolic. A reflector 22 is also shown that is spherical and parabolic, the generators in this are placed in various positions and the emitted and directed waves are unpolarized, similar to ordinary light. The apparatus for generating and directing the electromagnetic waves may be placed on the ship or may be placed at a central point in a harbor and used to "illuminate" the entire harbor. The reflectors such as 22 and 23 may be made of metal of any desired form, such as of metallic wires. The waves are directed upon any object desired, such as ship S. The waves are reflected from the conducting portions of the ship S into the lenses L of camera-like structure 18, 19, 28. The lens, or lenses L may be made of paraffin, bitumen, glass, ebonite, etc. One or more lenses, having the same or different refractive index may be used, as in ordinary visible light optics. The body of the camera should be either made of metal or covered with a suitable metallic sheeting or foil. A telescopic joint is indicated at 18, and this type of structure may be used. As an alternative structure, a bellows made of metallic sheeting or foil, or of other material and covered with metallic foil, is illustrated at 19. The camera hous-

ing or body may be made very long and tapering, as indicated by the right hand portion of Figure 5. This is indicated by 20. This will compensate for the extra long wave lengths used as compared to visible light waves.

Instead of the plane polarizing reflector such as 23, we may have the waves generated in all planes. In other words, the electromagnetic waves may be unpolarized, and a spherical reflector such as 22 provided. This is used to direct the waves in desired directions, such as on the object S.

There is fitted into the end of the camera-like structure just described the different modifications of apparatus described and illustrated in Figures 1 to 4 inclusive, also that described in connection with Figures 6 to 9 inclusive. However, the apparatus shown in Figures 1 to 4 is rather expensive, due to the fact that very many resonators are used. A less expensive apparatus is shown in Figure 5. This consists of a series of coils c each provided with a spark gap g and a neon or similar tube which becomes luminous when traversed by the current that is generated in the coil c. The tube is designated by reference character t. These coils are arranged on arms 25, of which there may be a plurality. The arms are readily rotated by means of motor 24, which rotates the shaft to which arms 25 are attached. In Figure 5 two arms are shown at 30 right angles to each other, each carrying a number of coils. If the beam of waves is plane polarized, as by the reflector 23, then the coils on the horizontal arm shown in the figure will respond vigorously and this will be indicated by the glow of the neon tube t. If, however, the waves are vibrating in all planes, i. e. they are unpolarized, the coils will be activated in any position, and the tubes will glow correspondingly. In other words, the tubes will all glow, only those being extinguished or partly extinguished as are in the low lights of the picture. Therefore, when unpolarized waves are used, the type of receiver shown in Figure 5, in which the arms 25 carry the coils c and tubes t through an entire circle, may be used. That is, each coil describes a complete circle, and the image is built up in a series of concentric circles. If, however, a transmitter such as that shown at 23 and 24 is used, the waves are polarized in a vertical plane, and only the coils shown in the horizontal arm of Figure 5 (shown in cross section) would give a spark at their spark gap, and cause their tubes t to glow. Obviously, as each arm assumes a certain position on being rotated, the tubes borne by it will glow. For this reason, an arrangement similar to that used in television is employed, whereby the arms 25 are made of much greater length, and the visual field is small compared with their length. Arms or disks, such as d of Figure 6 60 may be used.

Figures 6, 6a, 6b, 6c and 6d give a clearer illustration of this. Here the visual field is represented by f somewhat similar to the general methods of television. It will be noticed that the coils c are shown with their spark gaps g in a horizontal (here shown) or other plane. That is, they traverse it in a definite direction, and their paths are straight lines. Arms or disks may be used. Figures 6, 6a, 6b, 6c and 6d show the disk d carrying a series of coils. Figures 6, 6a and 6d represent the side of the disk that faces the lens L of Figure 5. The spark gaps g are clearly illustrated. It will be noted that they traverse the image field f in a horizontal posi- 75

tion. Figure 6b shows the side of the disk facing the observer and the tubes *t* are plainly indicated. It is the luminosity in those tubes that produces the luminous image. The disk acts to hide the 5 spark produced in the gap. The face of the disk facing the observer may be painted or otherwise colored black or any other desirable color to intensify the illumination of the tubes *t*. It is to be noted that the visual field or the area where 10 the image is to be produced is much smaller than the diameter of the disk *d*. All coils traverse the field in the same lines, for instance, here they are all horizontal. More than one row of coils may be used, and they may be arranged in a "staggered" 15 manner so that a real fine, detailed, sharp image is produced, if desired. Or, they may be arranged in a spiral line. Figures 6, 6a and 6d show both of those arrangements. Figure 6c shows a plan view of one of the coils, and indicates the manner 20 of coil *c* passing through and being supported by disk *d*; it also indicates that the spark gap *g* is located towards the lens *L* and that the neon or other tube *t* is located on the opposite side of the disk or other support. This neon tube 25 *t* may be attached to the coil *c* in any manner and at any portion of the coil desired. It may be connected by wires to the coil at any portion of the coil *c*, the coil being otherwise entirely separate therefrom. It is obvious that the vertical 30 row of coils of Figure 6a is traversing the image field, while the row shown at an angle of 45 degrees thereto will traverse the field in such manner that each tube will "draw" or "scan" luminous lines between those already "drawn" by 35 the vertical row. As many coils as desired may be employed and in any configuration desired, with the result that almost any degree of detail may be attained.

It will be observed that in order to light the 40 neon or other tubes in the field *f* of Figure 6, that the transmitter 24 of Figure 5 should be turned in a horizontal position. In this manner all of the energy radiated from conductors 24 is made to give the fullest effect upon coils *c* 45 with their attendant luminous tubes *t*. All of the energy from 24 is sent in a definite direction by reflector 23, instead of being scattered in all directions as in broadcasting. Furthermore, this energy is concentrated, and is also polarized in a 50 plane that will give the greatest results at the receiving coils *c*.

Figures 7, 7a, 7b, 7c and 7d show some of the types and manner of arrangement of the various resonators. Figure 7 shows a coil somewhat like 55 that of Figure 4. The spark gap (in air) is shown at the top of the figure, while the neon or other tube *t* is shown at the opposite end of the coil. Fig. 7a is a side elevation of Figure 7. The carrier arm is shown in cross section in the 60 form of a U in the center of the coil. It is to be noted particularly that the tube *t* may be attached to any portion of the coil *c* desired to produce the most desirable illumination. The coil in this figure is shown attached to the tube 65 by a shunting wire circuit.

Figure 7b shows a single turn coil. The tube *t* is here shown as forming a part of the coil, but may be shunted across any portion of the coil desired, and is not limited to the form shown. 70 Figure 7c shows a single turn coil which is entirely in front of the carrier arm, while a tube *t* of neon or other tube, is shown to the rear of the arm, and this tube is connected in shunt to the coil *c*. Figure 7d shows a circular single turn 75 coil which surrounds the carrier arm (here shown

as T shaped), while the neon or other tube *t* is shunted around the main coil. Some of the many possible forms of the carrier arm 25 are shown in this figure.

Figure 8 illustrates a carrier arm with some of the many possible coils *c* and associated neon or other tubes *t* that may be used. *a* is the shaft upon which the arm is mounted, and which rotates together with the coils at a suitable speed. If plane polarized waves are used, only a small portion of the arm is provided with coils *c*. However, both ends of the arm may be provided with coils in such manner that the lines described by the coils on one end may pass between the lines described by those on the other with the result that more lines, and consequently more definition are added to the picture. If heterogeneously polarized waves are utilized, the coils *c* are placed all along the full length of the arm, so that the image is made up of concentric circles of light produced by the neon tubes. Moreover, those concentric circles are "staggered" in the manner just described in order to produce a greater number of lines in the visual field, and thus give more definition to the image.

It is to be noted that the devices illustrated in Figures 1 to 4 are to be used in the camera-like structure illustrated in Figure 5. In other words the elements may be stationary or movable. It is also to be noted that the invention also includes a plurality of stationary elements of a nature similar to those illustrated in Figures 7 and 8, which contain a spark gap in addition to an illuminable element. It is well known that the spark gap is important, due to its function of building up the electric charge that is collected from the electromagnetic waves that traverse the coil.

This application is a continuation in part of my application Serial Number 509,163, filed October 20, 1921 for Electric wave device, and since abandoned, and contains subject matter disclosed in part by my informally filed application of September 29, 1922 for Hertzian wave apparatus.

Figure 9 shows a plurality of metallic elements 26 connected by wires 28 and 29. Figure 9a illustrates a modification in which the metallic elements 26 are unconnected. This constitutes a rotatable arm consisting of a glass or other transparent tube 27, which contains neon or other gas partially exhausted to produce the greatest illumination (at low pressure). This is mounted upon shaft 30 carrying insulated collector ring 32, together with brush 31. Current is conveyed through 31, 32, 28 to one series of elements 26, and through shaft 30, wire 29 to the other series of elements. Thus the auxiliary current may be passed to the electrodes. Either 30 or 31 may be connected to the ground if desired. This rotating element is placed in the plane of the invisible electromagnetic wave image to render it luminous. As shown in the figure, in the upper portion of the tube 27, the electrodes 26 may be unconnected to the external circuit. In such case, the rotating element would simply consist of a rotating tube carrying a plurality of unconnected electrodes in neon or other suitably illuminable gas.

Having described my invention, I claim as new and desire to secure by Letters Patent:

1. In combination: means for forming an invisible image of electromagnetic waves reflected from objects and a plurality of resonator lights placed substantially in the plane of said invisible image to produce a visible image.

2. In combination: means for forming an invisible image of electromagnetic waves reflected from objects and means placed substantially in the focal plane of said invisible image to convert said invisible image into a visible image by the action of said electromagnetic waves constituting said invisible image upon the said means.

3. In combination: means for forming an invisible image of electromagnetic waves reflected from objects and means placed substantially in the plane of said image for converting said invisible image into a visible image, and means for excluding extraneous electromagnetic waves from said image plane.

4. The method of perceiving objects by means of radio waves, which consists in generating electromagnetic waves, concentrating said waves into a dirigible beam directing said beam upon desired objects in order that they may be reflected herefrom, converging said reflected waves into an invisible image, converting said electromagnetic wave image into a visible image by suitable resonator-light elements.

5. In combination: means for forming an invisible image of electromagnetic waves reflected from objects and a plurality of moving resonator-lights placed substantially in the plane of said invisible image to convert said invisible image into a visible image.

6. In combination: means for forming an invisible electromagnetic wave image, a rotatable element substantially in the plane of said image carrying a plurality of resonators, each of said resonators having associated therewith an illuminable element which becomes illuminated by the current generated in said resonators, thus converting said invisible image into a visible image.

7. A luminous image forming device consisting of a rotatable disk, said disk being placed substantially in the focal plane of an invisible electromagnetic wave image, a plurality of resonator-light elements borne on said disk and arranged in a staggered relation.

8. A luminous image forming device for converting an invisible electromagnetic wave image into a visible light image consisting of a disk, a plurality of resonator-light elements arranged in a spiral line on said disk, said device being placed substantially in the focal plane of an invisible electromagnetic wave image.

9. Means for converting an invisible electromagnetic wave image into a visible light image, consisting of a rotatable element, a plurality of elements borne on said rotatable element and each consisting of a coil having a spark gap included therein with an associated circuit containing an illuminable lamp.

10. Means for converting electromagnetic waves into light when rotated substantially in the plane of an electromagnetic wave image comprising a rotatable element consisting of an arm, a plurality of resonators borne on said rotatable element, each of said resonators being provided with an illuminable element, for the purpose of rendering said invisible electromagnetic wave image visible.

11. Means for converting electromagnetic waves into light when rotated substantially in the plane of an electromagnetic wave image comprising a rotatable disk, a plurality of resonator-light elements borne on said rotatable disk and arranged in a staggered relation. 5

12. A device for rendering an invisible electromagnetic wave image visible when placed substantially in the plane of said image which consists of a plurality of elements for transforming 10 the said electromagnetic waves into electric currents and for converting said currents into visual light.

13. A device for rendering invisible electromagnetic wave images visible, which consists of means 15 for forming invisible electromagnetic wave images, a transparent body having a chamber therein filled with an illuminable gas at suitable pressure and a plurality of metallic bodies, said bodies corresponding and coinciding with the elemental areas of said images, electrical discharges taking place between said bodies resulting in luminous discharges in said gas in accordance with said invisible image, thus producing a corresponding visible image. 25

14. A device for converting an invisible electromagnetic wave image into a visible image consisting of means for forming an invisible electromagnetic wave image, a plurality of electrodes 30 arranged in the form of a plane corresponding to the plane of said invisible image, said electrodes having a number corresponding in general to the number of elemental areas of said invisible image and enclosed in a transparent body containing a 35 suitable gas at a suitable pressure to produce a varying glow therein in accordance with said invisible image, said glow being due to the electric currents generated in said gas by said electromagnetic wave image, the result being a visible image. 40

15. A device for converting an invisible electromagnetic wave image into a visible image, consisting of means for forming an invisible electromagnetic wave image, a transparent body containing a suitable gas at a suitable low pressure for the 45 production of glow discharges placed in the focal plane of said invisible image and a plurality of metallic bodies arranged in a plane in said gas, said bodies having a number corresponding in general to the number of elemental areas of said 50 invisible image.

16. A device for rendering invisible electromagnetic waves visible, consisting of a lens forming an image of electromagnetic waves, a plurality of metallic bodies in a body of illuminable gas and arranged in the form of a plane therein, said bodies being divided by electrical connections into two groups, a source of biasing current connected to said groups of electrodes, the energy of 55 said waves charging said conductors and causing a luminous discharge taking place in said gas corresponding to the distribution of the electromagnetic wave energy in said image, said luminous discharge constituting a visible image. 60 65

ALOYSIUS J. CAWLEY.
